UNITED STATES PATENT OFFICE.

ALBEN E. LUNDELL, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

1,356,639.

Specification of Letters Patent. Patented Oct. 26, 1920.

Application filed November 14, 1916. Serial No. 131,203.

To all whom it may concern:

Be it known that I, ALBEN E. LUNDELL, a citizen of the United States, residing at New York, in the county of Bronx and State of New York, have invented certain new and useful Improvements in Telephone-Exchange Systems, of which the following is a full, clear, concise, and exact description.

This invention relates to telephone exchange systems, and particularly to means for applying ringing current to the called line. It has been found in practice that the number of final switches is greater than the number of certain of the intermediate switches, and therefore it has heretofore been proposed that the ringing equipment be placed at one of such intermediate switches. In order to apply the ringing current automatically at the proper time, a steering switch has been associated with such intermediate switch, which advanced one step for each switch used in the connection being built up, and when connection was made with the called line, advanced to the ringing position. Thus, ringing current was invariably applied when a predetermined number of switches had been set. In systems which include private branch exchange lines, however, the number of switches used in establishing a connection when a private branch exchange line is called is different from that used in an ordinary connection.

The object of the present invention is to insure the proper operation of the ringing equipment at the intermediate switch in such a system, irrespective of the number of switches used.

To attain this object there is provided, in accordance with this invention, a controlling circuit successively established or maintained in a given condition from the intermediate switch to and through the intervening switches to the final switch in the series, by means of which the ringing equipment is rendered effective upon the completion of the connection to the wanted line.

In the embodiment shown herein the invention is applied to a machine switching system, and when the connection is extended to the switch succeeding that at which the ringing equipment is located, the control magnet of the steering switch is energized, such switch being arranged to ad-

vance upon the deenergization of the control magnet. This magnet is maintained energized in a circuit at each succeeding switch, closed before the corresponding circuit at the preceding switch is opened, this circuit being opened when the connector is set on the called line to advance the steering switch to the ringing position. If such line is busy, means is automatically rendered operative to prevent such ringing current from being applied to the called line, and a busy tone is instead automatically applied to the calling line.

Referring to the drawings, Figures 1 and 2 taken together illustrate diagrammatically one embodiment of the invention. In the embodiment shown, the line of the calling party A, upon initiating a call, may be connected to an operator's position in any well-known manner. When the operator learns the number of the wanted line, she associates her sender 113 by means of key K with the leads 154 and 155 terminating in a first selector not shown. This selector is then set by the operator to pick out an idle incoming selector IS at the distant office. The sender may be of the well-known finger wheel type which, upon restoring, interrupts the line circuit a number of times corresponding to the number of the digit of the called line involved. When the call has been extended to the incoming selector IS at the distance office, the stepping relay 100 thereat becomes energized over the following circuit: free pole of battery, contact 101 of key K, conductor 155, arm 103 of the side switch of the selector IS and its first contact, stepping relay 100, arm 104, conductor 154, spring 107 and its lower contact, contact 108 of the operator's sender to ground. Relay 100 in attracting its armature energizes a relay 109, which, in attracting its right armature, locks itself to ground over the armature and back contact of relay 110, and, in attracting its left armature, connects the back contact of relay 100 to the primary stepping magnet PM of the selector IS.

The operator now transmits the digit of the wanted number with which the incoming selector IS is concerned by means of her sender 113, which interrupts the circuit of relay 100 in the well-known manner. Upon each retraction of the armature of

relay 100, an impulse is transmitted to magnet PM, which steps the brushes 113', 114, 115 of the selector IS in a primary direction into operative relation to the desired 5 group of trunks. Relay 112 is included in series with magnet PM, and being slow-acting, is maintained energized, notwithstanding the interruptions in its circuit, as the armature of relay 100 vibrates. This relay, 10 in attracting its armature, energizes the side-switch escapement magnet 116 of selector IS, which is constructed to release the side switch upon its deenergization in the well-known manner. When the sender 113 15 restores and maintains relay 100 energized, slow relay 112, after a slight interval, becomes deenergized, and, in retracting its armature, deenergizes the escape magnet 116 which passes the side switch to position 20 2. In position 2, arm 117 connects the secondary magnet SM of the selector IS in circuit with the interrupter 118, and arm 119 energizes the escape magnet 116 over the off-normal contact SON, which is 25 opened upon the first secondary step of the selector IS. Busy trunks are those upon whose test multiples 120 ground is present, as will hereinafter appear. Consequently, the escape magnet 116 is maintained energized as long as busy trunks are encountered. When the first ungrounded test multiple 132 is reached, magnet 116 becomes deenergized, passing the side switch 30 into position 3. Arm 117, in leaving position 2, opens the circuit of magnet SM, thus stopping the selector with the brushes 113, 114 and 115 upon the multiples 121, 122 and 120 of the selected trunk. In position 3, arm 119 grounds multiple 120, thus 35 causing the seized trunk to test busy to other selectors and energizes release relay R'R', which, in attracting its armature, interposes a break in the circuit of release magnet R'M' of the selector S. In position 40 45 1 of the selector S, side-switch arm 123 thereof closes the following circuit for the escape magnet 116 of the selector IS: ground, arm 123 and its first contact, multiple 122, brush 114, arm 124 and its third contact, conductor 125, magnet 116, free 50 pole of battery. The escape magnet 116 becomes energized when this circuit is closed, but does not release the side switch. The operator now transmits the next digit of the wanted number. Upon each retraction 55 of the armature of relay 100, an impulse is transmitted over the following circuit to the primary magnet P'M' of selector S: armature and back contact of relay 100, left armature and front contact of relay 109, conductor 126, arm 127, brush 113, terminal 121, arm 128, slow relay 129, magnet P'M', free pole of battery. The selector S is thus stepped in a primary direction in 60 65 operative relation to the desired group of

trunks 130, 131, 132 terminating in connectors having access to the desired line. The relay 129 is slow-acting and remains energized during the transmission of the impulses. In attracting its armature, it energizes the escape magnet 133 of the selector S, which is constructed to release the side switch upon its deenergization in the well-known manner. 70

When the sender 113 restores and maintains the circuit of relay 100 closed, relay 129, after an interval, retracts its armature, thus deenergizing magnet 133, which releases the side switch into position 2. In position 2 the interrupter 134 is connected 75 to the secondary magnet S'M' over the side-switch arm 135, and steps the brushes 136, 137, 138 over the selected trunk group. In position 2 escape magnet 133 is again energized over arm 139 and secondary off-normal contact S'O'N'. Busy trunks are 80 those upon whose test multiples ground is present. Consequently, the escape magnet 133 is maintained energized as long as busy trunks are encountered. When the first ungrounded test multiple 132 is reached, magnet 133 is deenergized and releases the side switch into position 3. It will be noted that side-switch arm 123 of the selector S, in its 85 second position, maintains ground upon conductor 125 leading to the escape magnet 116 of selector IS. This arm 123 engages its second contact before it leaves its first contact, and engages its third contact before leaving its second contact. Thus, as 90 this arm reaches position 3, the escape magnet 116 is held energized over the following 95 circuit: free pole of battery, left winding of magnet 116, conductor 125, arm 124 and its third contact, brush 114, multiple 122, arm 105 123 and its third contact, brush 137, multiple 131, side-switch arm 200 of connector C and its first contact to ground. Arm 139, in its third position, grounds the multiples 132 of the seized trunk to render the 110 same busy, and also operates a release relay R'R'' of the connector, which, in attracting its armature, interposes a break in the circuit of release magnet R'M'' of the connector. 115

The operator now transmits the tens digit of the called number. Upon each retraction of the armature of relay 100, an impulse is transmitted over the following circuit to primary magnet P'M'' of the 120 connector: armature and back contact of relay 100, left armature and front contact of relay 109, conductor 126, arm 127 and its third contact, brush 113, multiple 121, arm 128 and its third contact, brush 136, 125 multiple 130, arm 201 and its first contact, conductor 202, right winding of slow relay 203', magnet P'M'', free pole of battery. Relay 203' being slow acting, is maintained energized during the transmission of 130

the impulses, and, in attracting its armature, energizes the escape magnet 203 of the connector side switch which is constructed to release the side switch upon its deenergization in the well-known manner. The connector brushes 204, 205, 206 are thus driven in a primary direction into operative relation to the group of terminals containing those of the desired line 207, 208, 209. When the sender restores and maintains relay 100 energized, slow relay 203', after an interval, becomes deenergized, and, in retracting its armature, deenergizes the escape magnet 203 which passes the side switch into position 2, in which position arm 201 substitutes the secondary magnet S^2M^2 for the primary magnet P^2M^2 in the stepping circuit. Arm 200 in position 2 maintains ground upon conductor 140 connected to the escape magnet 116, thus holding the same energized.

The operator now transmits the units digit of the wanted number. Upon each retraction of the armature of relay 100 an impulse is transmitted over the circuit traced to the arm 201, from whence it passes over conductor 210 and the left winding of relay 203' to the secondary magnet S^2M^2 . Relay 203' becomes energized upon receipt of the first impulse, and energizes the escape magnet 203 as before. The brushes 204, 205 and 206 are thus driven into engagement with the multiples 207, 208 and 209 of the desired line. When the sender restores and maintains relay 100 energized, slow relay 203', after an interval, becomes deenergized, and, in retracting its armature deenergizes magnet 203, which passes the side switch into position 3, in which the test of the selected line takes place. Arm 200, in moving off its second contact, removes ground from conductor 140, connected to the escape magnet 116 of the selector IS. The escape magnet thereupon deenergizes and passes the side switch into position 4. When the sender 113 restores, after transmitting the units impulses, the operator throws the key K, so that the springs 101, 107 engage with their upper and lower contacts, respectively, thus disconnecting the sender from the leads 154, 155 and connecting the battery 157 thereto. Arm 104, in position 4, closes the following circuit for relay 141; free pole of battery, relay 141, upper left-hand winding of repeating coil $R'C'$, arm 104 and its fourth contact, conductor 154, spring 107 and its upper contact to ground. Relay 141, in attracting its armature, energizes ringing relay 142 over the following circuit: ground, armature and front contact of relay 141, conductors 143, 144, armature and back contact of ringing cut-off relay RCO, armature and back contact of relay 145, conductor 146, relay 142, free pole of battery.

Relay 142, in attracting its armatures, connects the free pole of generator 147 to the side-switch arm 200 and ground to the arm 201 preparatory to projecting the ringing current over the selected line. In parallel with the relay 142, a relay 150 is energized, and in attracting its left armature, energizes relay 110. Relay 110, in attracting its left armature, opens the locking circuit of relay 109 and interposes a break in the circuit of release magnet RM.

As stated, in position 3 of the connector side switch, the called line is tested. If the selected line is idle, full potential is present upon the test multiple 209 thereof, and the test relay 211 becomes energized over the following circuit: free pole of battery, cut-off relay CO, multiple 209, brush 206, both windings of relay 211 in series, arm 215 and its third contact to ground. The test relay 211, in attracting its right armature, shunts out its right-hand high-resistance winding, thus so reducing the potential upon the test multiples 209 of the selected line that it will test busy to other connectors. In position 3 arm 216 closes a circuit to energize relay 212. Relay 212, in attracting its right armature, closes the following circuit for connector escape magnet 203 which is constructed to release the side switch from position 3 to position 4, upon its energization: ground, right armature and front contact of relay 212, left armature and front contact of relay 211, magnet 203 to free pole of battery. In position 4, arms 201 and 200 extend the ringing circuit to the called line, whereupon the bell 216 thereat is rung. The ringing circuit is as follows: free pole of ringing generator 147, relay RCO, lower armature and front contact of relay 142, arm 124 and its fourth contact, brush 114, multiple 122, arm 123 and its third contact, conductor 140, brush 137, multiple 131, arm 200 and its fourth contact, brush 205, multiple 208, condenser 217, bell 216, multiple 207, brush 204, arm 201 and its fourth contact, multiple 130, brush 136, arm 128 and its third contact, multiple 121, brush 113, arm 127 and its fourth contact, upper armature and front contact of relay 142 to ground. When the subscriber at substation B removes his receiver from the hook, the relay RCO becomes energized, and, in attracting its armature, removes the shunt from about relay 145, which thereupon becomes energized in series with relay 142, and in attracting its armature shunts out relay 142 and locks itself up to ground at the armature and front contact of relay 141. Relay 142, in retracting its armatures, disconnects the ringing generator 147 from the called line and connects thereto the repeating coil $R'C'$. Upon the retraction of the armatures of relay 142, talking current is fed to the called line over the following path: free

5 pole of battery, lower right-hand winding of repeating coil $R'C'$, called supervisory relay 151, lower armature and back contact of relay 142, arm 124 and its fourth contact, brush 114, multiple 122, arm 123 and its third contact, conductor 140, brush 137, multiple 131, arm 200 and its fourth contact, brush 205, multiple 208, through the 10 telephonic apparatus at substation B, multiple 207, brush 204, arm 201 and its fourth contact, multiple 130, brush 136, arm 128 and its third contact, multiple 121, brush 113, arm 127 and its fourth contact, upper armature and back contact of relay 142, 15 upper right-hand winding of repeating coil $R'C'$, to ground. Relay 151, in attracting its armature, closes the following circuit leading to the operator's position: ground, right armature and front contact of relay 150, armature and front contact of relay 151, impedance coil 152, lower left winding of repeating coil $R'C'$, arm 103 and its fourth contact, spring 101 and its lower contact, free pole of battery. This 20 circuit may operate the usual signal for the operator to indicate to her that the called party has responded. Talking current is fed to the calling party from battery 157 over the windings of repeating coil RC .

25 30 Upon the conclusion of the conversation the subscribers replace their receivers and operate the usual signals before the operator, who thereupon operates the key K to break the circuit of relay 141. Relay 141, in re- 35 tracting its armature, deenergizes relay 150, which, in retracting its left armature, deenergizes relay 110 which closes the release circuit of the selector IS as follows: release magnet RM , primary off-normal contact PON , right armature and back contact of relay 109, left armature and back contact of relay 110 to ground. The release magnet, in energizing, withdraws the pawls from the shaft of selector IS, and also restores the 40 side switch in the well-known manner. The restoration of the selector IS deenergizes relay $R'R'$ of the selector S' , which, in re- 45 tracting its armature, energizes the release magnet $R'M'$, of said selector over the off-normal contact $P'ON'$. Magnet $R'M'$, in energizing, locks itself in a circuit including such off-normal contact, which opens when the shaft of the selector reaches its normal position, thus deenergizing such magnet. 50 55 Similarly, the restoration of selector S' deenergizes relay R^2R^2 of the connector C , which, in retracting its armature, energizes the release magnet R^2M^2 of the connector over the off-normal contact $P^2O^2N^2$. This 60 magnet similarly locks itself over such off-normal contact and restores the connector side switch. When the connector brush shaft reaches its normal position and opens the off-normal contact $P^2O^2N^2$, release magnet R^2M^2 is deenergized. If the selected 65

line is busy, insufficient potential is present upon the test multiple 209 thereof to energize the test relay 211. Consequently, this relay remains inert, and at its back contact connects the grounded pole of the battery 70 to the ringing cut-off relay RCO over the right armature and front contact of relay 212, left armature and back contact of relay 211, resistance 213, arm 200 and its third contact, multiple 131, brush 137, conductor 75 140, arm 123 and its third contact, multiple 122, brush 114, arm 124 and its fourth contact, lower armature and front contact of relay 142, relay RCO , ringing generator 147 to ground. The marginal relay RCO becomes energized when this circuit is closed, and in attracting its armature, removes the shunt from about relay 145, which thereupon energizes in series with relay 142. In attracting its armature relay 145 shunts out 80 relay 142 and locks itself to ground at the armature and front contact of relay 141 as described. Relay 142, in retracting its armatures, connects the repeating coil $R'C'$ to conductors 148 and 149, whereupon the following circuit is closed from the source of busy tone current 214 to notify the operator that the selected line is busy: ground, secondary winding of the source of busy tone current 214, condenser 215, left armature 95 and front contact of relay 212, arm 201 and its third contact, multiple 130, brush 136, arm 128 and its third contact, multiple 121, brush 113, arm 127 and its fourth contact, upper armature of relay 142 and its back 100 contact, upper right winding of repeating coil $R'C'$ to ground. The operator hears this tone by induction through the windings of repeating coil $R'C'$, and informs the calling party that the desired line is busy, and 105 releases the connection as described.

Assuming now that the called line is located in a private branch exchange. In this case the operation is the same as that described, except that the selector IS, instead of selecting selector S , picks out another selector similar to S , which has access to the connectors C' in the private branch exchange. Assuming, therefore, that a selector similar to S has been set on the multiples 110 218, 219 and 220 of a connector in the private branch exchange, when the brush 137 thereof engages the multiple 219, the following circuit is closed to maintain the escape magnet 116 of incoming selector IS energized: ground, arm 237 and the first contact of the side switch of connector C' , relay 239, multiple 219, brush 137, arm 123 and its third contact, multiple 122, brush 114, arm 124 and its third contact, conductor 125, 125 magnet 116, free pole of battery. The relay 239 interposes a break in the circuit of release relay R^3R^3 of the connector.

The sender 113 is now actuated by the operator to transmit the tens digit of the 130

wanted line. Upon each retraction of the armature of relay 100 an impulse is transmitted over the following circuit to the primary stepping magnet P^3M^3 of the connector C' at such private branch exchange: armature and back contact of relay 100, armature and front contact of relay 109, conductor 126, arm 127 and its third contact, brush 113, multiple 121, arm 128 and its third contact, brush 136, multiple 218, arm 221 of the connector side switch, conductor 222, right winding of slow relay 223, magnet P^3M^3 , free pole of battery. Relay 223 remains energized during the transmission of the impulses and closes a circuit to energize connector side-switch magnet 230. The magnet P^3M^3 thus steps the connector brushes 224, 225 and 226 in operative relation to the group containing the desired line 227, 228 and 229. When the sender 113 restores and maintains relay 100 energized, the slow relay 223, after an interval, becomes deenergized and opens the circuit of escape magnet 230, which releases the side switch into position 2, in which position arm 221 substitutes the secondary stepping magnet S^3M^3 for the primary magnet in the stepping circuit. The operator now transmits the units digit of the wanted line, and upon each retraction of the armature of relay 100 an impulse is transmitted over the path traced to the connector side-switch arm 221, from whence it passes over conductor 231, left winding of slow relay 223, magnet S^3M^3 , free pole of battery. Relay 223, as before, remains energized during the transmission of the impulses, and, in attracting its armature, energizes escape magnet 230. When the sender restores and maintains relay 100 energized, slow relay 223, after a slight interval, retracts its armature, deenergizing magnet 230, which passes the side switch into position 3. If the selected line is idle, unshunted potential is present upon the test multiples 229 thereof, and the following circuit is closed: free pole of battery, cut-off relay 232, multiple 229, brush 226, windings of test relay 233, arm 234 and its third contact to ground. Relay 233, in attracting its right armature, shunts out its high-resistance winding which so reduces the potential upon the multiples 229 of the selected line as to cause it to test busy to other connectors. In attracting its left armature, this relay closes the following circuit to energize the escapement magnet 230: free pole of battery, magnet 230, left armature and front contact of relay 233, right armature and front contact of relay 235, to ground, relay 235 being energized over arm 236 and its third contact at this time. The escape magnet 230 is constructed to release the side switch into position 4 upon its energization. As hereinbefore described, when the arm 237

which corresponds to arm 200 of the connector C passed off its second contact, the escape magnet 116 of the selector IS becomes deenergized and releases the side switch of said selector into its fourth position, in which relay 142 becomes energized, as described, to connect ringing generator 147 to the called line D to ring the bell 238 over the following circuit: free pole of generator 147, relay RCO, lower armature and front contact of relay 142, arm 124, brush 114, multiple 122, arm 123 and its third contact, conductor 140, brush 137, multiple 219, relay 239, arm 237 and its fourth contact, brush 225, multiple 228, bell 238, and condenser 240 at station D, multiple 227, brush 224, arm 221 and its fourth contact, multiple 218, brush 136, arm 128 and its third contact, multiple 121, brush 113, arm 127 and its fourth contact, upper armature and front contact of relay 142 to ground.

Upon the removal of the receiver at substation D, ringing cut-off relay RCO is energized as described, from which point the operations are the same as those traced. The function of relay 239 is to remove relay 241 from the talking circuit. Talking current is fed to the called station at the private branch exchange over the windings of repeating coil $R'C'$, the called supervisory relay 239 being included in this circuit. Upon the conclusion of the conversation and the replacement of the receiver by the called party, relays 151 and 239 become deenergized, the former operating the usual supervisory lamp before the operator and the latter interposing a break in the circuit of relay R^3R^3 to prevent premature release. The operator now, by means of the key K, restores the selectors IS and S. When the selector S is restored, the circuit of relay 241 is interrupted, whereupon the following circuit is closed for the release relay R^3R^3 of the connector: free pole of battery, relay R^3R^3 , arm 240 and its fourth contact, armature and back contact of relay 241, left armature and back contact of relay 239, ground. Relay R^3R^3 , in attracting its armature, energizes release magnet R^3M^3 of the connector over the off-normal contact $P^3O^3N^3$, which thereupon energizes, and in attracting its armature, locks itself over such off-normal contact. When the connector brush shaft restores and opens this contact, release magnet R^3M^3 becomes deenergized.

If the selected line had been busy, the potential present upon the multiple 229 thereof would have been insufficient to energize test relay 233, as described. The relay 235, in the third or testing position, is however energized over arm 236, and maintains relay 239 energized over the following circuit to prevent premature release: ground, right armature of relay 235 and its front contact, left armature of relay 233 and its

back contact, resistance 242, arm 237 and its third contact, relay 239, multiple 219, brush 137, conductor 140, arm 123 and its third contact, multiple 122, brush 114, arm 124 and its fourth contact, lower armature and front contact of relay 142, relay RCO, ringing generator 147 to ground. Relay RCO operates as hereinbefore described, resulting in the deenergization of relay 142, which 10 connects the right half of the repeating coil to the conductors 148, 149. The attraction of the left inner armature of relay 235 connects a source of busy tone current 243 in circuit with the repeating coil R'C', to indicate to the operator that the desired line is busy. This circuit is as follows: ground, secondary winding 244, condenser 245, inner left armature of relay 235, arm 221 and its third contact, multiple 218, brush 136, arm 128 and its third contact, multiple 121, brush 113, arm 127 and its fourth contact, upper armature and back contact of relay 142, repeating coil R'C' to ground. The operator will then inform the calling party of 15 the busy condition of the desired line, and will break down the connection by actuating the key K and restoring the selectors IS and S. The restoration of these selectors deenergizes relay 239, which, in retracting its left armature, energizes the release relay R³R³ of the connector over the following circuit: ground, left armature and back contact of relay 239, armature and back contact of relay 241, outer left armature of 20 relay 235, relay R³R³, free pole of battery. Relay R³R³, in attracting its armature, operates the release magnet R³M³ as before described, and also restores the side switch. 25

From the foregoing it is evident that the 30 circuit arrangement of this invention is particularly advantageous in machine switching telephone exchange systems employing private branch exchange working, since the side switch of the incoming selector will remain in its third position until the last 35 set of impulses is sent, irrespective of the number of sets of such impulses, whereas in systems of the prior art, wherein the ringing equipment was located at the incoming 40 selector, the ringing control switch advanced one step for each set of impulses and invariably applied ringing current at the end of 45 a predetermined number of said sets of impulses.

50 55 What is claimed is:

1. In a telephone exchange system, the combination with telephone lines, link circuits terminating in automatic switches, a rotary auxiliary switch associated with each 55 of said automatic switches for controlling the same, means for interconnecting a calling and a called line over a number of said link circuits and automatic switches in series, a source of signaling current at an intermediate one of said link circuits, an elec-

tromagnetic responsive device at said intermediate link circuit adapted to operate its associated auxiliary switch to connect said source to said link circuit upon its deenergization, a closed circuit including said device 70 and the link circuits in series automatically established and maintained, and means for opening said circuit when connection is made with the called line to operate said device. 75

2. In a telephone exchange system, the combination with telephone lines, switches adapted to interconnect the same, a rotary auxiliary switch associated with each of said switches to control the same, a source of signaling current at an intermediate one of said switches, and an electromagnetic responsive device for operating its associated auxiliary switch to connect said source to said intermediate switch upon its deenergization, means for including said device in a closed circuit extended to each succeeding switch in series, and means for opening said circuit when connection is made with the called line to operate said device to connect 90 said source thereto. 95

3. In a telephone exchange system, the combination with telephone lines, link circuits, means for interconnecting a calling and a called line over a number of said link 100 circuits in series, a source of signaling current at an intermediate one of said link circuits, a steering switch at each of said link circuits to control the same, a magnet associated with the steering switch of the intermediate link circuit adapted to advance the same to connect said source to said link circuit upon its deenergization, means for energizing said magnet, means for maintaining said magnet energized including a 105 circuit at each succeeding link circuit, and means for deenergizing said magnet when the connector is set on the called line. 110

4. In a telephone exchange system, the combination with telephone lines, link circuits terminating in selective switches, means for interconnecting a calling and a called line over a number of said link circuits in series, a source of signaling current at an intermediate one of said link circuits, a multi-position steering switch at each of said link circuits to control the same, a magnet associated with the steering switch of said intermediate link circuit adapted to advance the same to connect said source to 120 said link circuit upon its deenergization, means for energizing said magnet, means for maintaining said magnet energized including a circuit at each succeeding link circuit, means for deenergizing said magnet when the connector is set on the called line, and means for preventing said signaling current from being applied to the called line automatically operated if such line is 125 busy. 130

5. In a telephone exchange system, the combination with telephone lines, automatic switches including selectors and a connector, stepping magnets therefor, a sender adapted to operate said magnets to set such switches to interconnect said lines, a source of signaling current at an intermediate selector, a side switch for each of said selectors to control the same, means for advancing the steering switch of said intermediate selectors when said selector is set to place said sender in operative relation to the magnets of the succeeding switches, means for maintaining said steering switch in said position while said succeeding switches are being set, and means for advancing said steering switch to connect said source of signaling current to the selected line when the connector is set thereon.
- 20 6. In a telephone exchange system, the combination with telephone lines, automatic switches including selectors and a connector, stepping magnets therefor, a sender adapted to operate said magnets to set such switches to interconnect said lines, a source of signaling current at one of said selectors, a side switch for said selector including an escapement magnet adapted to advance the side switch upon its deenergization, means for deenergizing said magnet when said selector is set to advance said side switch to place said sender in operative relation to the magnets of the succeeding switches, means for again energizing said escape magnet including a circuit at the succeeding switch, and for maintaining the same energized including a circuit at each succeeding switch, closed before the corresponding circuit at the preceding switch is opened, and means for deenergizing said escape magnet to advance said side switch to connect said source of signaling current to the selected line when the connector is set thereon.
- 45 7. In a telephone exchange system, the combination with telephone lines, link circuits including switches, a rotary auxiliary switch at each of said switches, means for interconnecting a calling and called line over a number of said link circuits in series, a source of signaling current at an intermediate one of said link circuits, means in-
- cluding the auxiliary switch at said intermediate link circuit adapted to connect said source to the conductors of said link circuit, a magnet for operating said switch when deenergized, a closed circuit therefor including said link circuits in series, and means for automatically maintaining said circuit closed until connection is made with the called line, and means automatically operated if the line is busy for preventing the operation of said magnet from becoming effective to apply current to the called line.
- 15 8. In a telephone exchange system, the combination with telephone lines, link circuits terminating in automatic switches, means for interconnecting a calling and a called line over a number of said link circuits and automatic switches in series, a rotary auxiliary switch associated with each of said automatic switches for controlling the same, a source of signaling current at an intermediate one of said link circuits, a device including the auxiliary switch at said intermediate link circuit adapted to connect said source to said link circuit upon its deenergization, a closed circuit including said device and the link circuits in series automatically established and maintained, and means automatically actuated when connection is made with the called line for rendering said circuit effective to operate said device.
- 25 9. In a telephone exchange system, telephone lines, link circuits terminating in automatic switches, each of said automatic switches being provided with a step by step auxiliary switch for controlling the same, means including said link circuits and automatic switches in series for interconnecting a calling and a called line, a source of ringing current at an intermediate switch of the series, and means located at said intermediate switch and controlled successively over said link circuits for connecting said source of ringing current to the series of link circuits when the called line is found.
- 40 In witness whereof, I hereunto subscribe my name this 13th day of November, A. D. 1916.

ALBEN E. LUNDELL.
